CONTAINER FILLING APPARATUS

Bruce De Haven Miller, Louisville, Ky., assignor
to The Girdler Corporation, Louisville, Ky., a
corporation of Delaware

Application June 5, 1943, Serial No. 489,770

24 Claims. (Cl. 226—116)

The present invention relates to apparatus for filling liquids into bottles or other containers under vacuum, and more particularly to an improved design and construction of a filler valve for that purpose.

Numerous forms of apparatus for filling liquids into containers under vacuum are available on the market or have been proposed, but none of those forms with which I am familiar has proven entirely satisfactory in operation in those cases in which it is essential to prevent air from leaking into the apparatus and becoming incorporated in the liquid in the reservoir and various passages of the filling apparatus, and in the container during the filling operation. One of the simplest forms of filling apparatus has means constantly operative to draw a vacuum, both when the container is in contact with the valve and when the container is withdrawn; there being no provision for closing off the passage to the evacuating mechanism. Examples of such constructions are shown in Patents 2,126,563 to Lee; 1,418,203 to Pennock, and 1,675,208 to Broadhurst. One of the disadvantages of this simple form of filling apparatus is due to the fact that it is practically impossible to maintain the proper degree of vacuum in the apparatus. Furthermore, there results considerable waste of the energy required in operating the evacuating mechanism. Another form of filling apparatus heretofore employed, has included valve means manually operable first to connect the container with the evacuating equipment, and then to close the evacuating passage and connect the container with the liquid supply. Examples of this type are shown in Patents 712,832 to Moore, and 1,232,105, 1,437,916 and 1,437,917 to Shelor. Modifications of this last mentioned form have included valve mechanisms operative mechanically, sometimes by movement of the filling apparatus itself and sometimes by movement of the container, for first connecting the container with the evacuating mechanism and then connecting it with the liquid supply. Examples of this type are shown in Patents 1,978,002 to Weaver; 619,474 to Fowler; 2,196,299 and 2,204,131 to Glunz; and 732,678 to Ford.

An important disadvantage of all the forms of filling apparatus above mentioned results from the fact that they are incapable of automatically rejecting broken or defective bottles or containers. Thus it is necessary to depend upon an operator to detect such defective containers and reject them. Frequently it is impossible for an operator to detect quickly any slight imperfections in a container, such as small cracks or irregularities

at the mouth of a bottle, and this frequently leads to filling of defective containers in such manner that undesirable amounts of air are introduced into the liquid in the containers or into the reservoir of the filling apparatus.

Attempts have been made to provide filling apparatus capable of automatically detecting and rejecting defective containers, as appears from Patent 668,303 to Beyer and some of the patents previously mentioned. None of those with which I am familiar has been capable of accomplishing such detection and rejection of defective containers without undue waste of energy of the evacuating mechanism and introduction of undesirable amounts of air into the liquid reservoir and other parts of the filling apparatus.

An object of the present invention is to provide a filling apparatus incorporating an improved form of filler valve which is completely automatic in its operation; is capable of filling liquids into bottles or containers under vacuum and to a definitely controlled level without permitting any leaking in of air or aeration of the liquid, either in the filling apparatus or container; does not have any of the other above mentioned objectionable features of previous forms of filling apparatus; and is capable of eliminating dripping after the filling operation is completed.

A further and more particular object of the invention is to provide an improved valve for vacuum filling apparatus, which is capable of automatically preventing the filling of broken or defective containers; does it in such manner as to conserve the energy of the evacuating equipment; prevents the passage of air through the liquid in the reservoir and various passages of the filling apparatus; and prevents introduction of any substantial amount of air into the reservoir of the filling apparatus above the liquid level.

Other objects and details of my invention will become apparent from the following description taken in conjunction with the accompanying drawings, in which

Fig. 1 is a vertical section through a bottling machine embodying my invention and showing in side elevation certain features thereof;

Fig. 2 is a central vertical section of a portion of the reservoir and on a larger scale; one of the filling tubes being shown in side elevation;

Fig. 3 is a central vertical section of one of the filling tubes on a still larger scale; the middle portion of the tube being omitted and the parts being shown in the positions they occupy when there is no container in the filling position;

Fig. 3a is an enlargement of a portion of Fig. 3;

Figs. 4, 5 and 6 are sections similar to portions of Fig. 3 and showing certain parts in successive positions which they occupy during the filling operation;

Figs. 7, 8 and 9 are sections on the lines 1—1, 8—8 and 9—9, respectively, of Fig. 2;

Figs. 10 to 14 inclusive are sections on the lines 10—10, 11—11, 12—12, 13—13 and 14—14, respectively of Fig. 3;

Fig. 15 is a perspective view of the outer of the two tubes of the nozzle;

Fig. 16 is a central vertical section through a modified form of filling apparatus embodying my invention;

Fig. 17 is a section on the line 17—17 of Fig. 16, and

Fig. 18 shows further modification of the upper part of the form shown in Fig. 16.

Although the apparatus of my invention may be employed to advantage in the filling of various kinds of liquids into bottles or containers, it is particularly advantageous for the filling of bottles with milk which has been deaerated to a very high degree, such as, for example, milk which has been treated by a process and apparatus such as shown and described in applications Serial No. 438,216 and Serial No. 439,836 of Paul F. Sharp, David B. Hand and Edward S. Guthrie, which applications are assigned to Cornell Research Foundation. Hence, the invention will be described herein as embodied in a vacuum filling apparatus for milk, although it is to be understood that it is not intended thereby to limit the invention to milk filling apparatus.

For purposes of illustration, my improved filler valve is shown as embodied in a milk filling apparatus of more or less conventional form, and only sufficient details of the general construction of this apparatus will be included herein to insure proper understanding of my invention.

As shown in Fig. 2, the reservoir of the apparatus is comprised of a tank 20 having a dome shaped cover 21 with a gasket 22 for sealing the joint between the tank and cover. During operation of the filling apparatus, the cover is held in sealing relation to the tank by the vacuum maintained in the reservoir. If it is desired to provide additional insurance against misplacement of the cover and against leakage at the joint between the cover and tank, any suitable clamping means may be provided. As is customary with apparatus of the form shown, the tank 20 is supported for rotation on a pedestal (see Fig. 1) bolted to a plate 23 welded or otherwise secured on the bottom of the tank.

For introduction of milk into the reservoir, there is provided a vertically extending stationary tube 24, which extends to a point adjacent the bottom of the reservoir. The upper part of this tube extends concentrically through a stationary T-shaped connection 25, and is held in place by means of a flange 26 which is welded on the tube and clamped between a clamping nut 27 and the upper end of the T-shaped connection 25. A gasket of any suitable form and material or other suitable means is provided for maintaining an air-tight seal between flange 26 and the end of the connection 25. The lateral of the T-shaped connection is provided with a clamping nut 30 for securing thereto the end of a pipe 31 leading to the evacuating mechanism, whereby a vacuum may be established and maintained in the reservoir through the passage surrounding tube 24, and the joint between pipe 31

and connection 25 is such as will prevent any loss of vacuum at this point.

In order to permit rotation of the reservoir, relative to the stationary tube 24 and connection 25, while at the same time insuring the necessary air-tight seal around the centrally located opening in the cover 21, there is provided a stationary sleeve 35 sweated or otherwise secured at its upper end in a recess in the lower end of connection 25. This sleeve projects down into the upper part of the reservoir and has a suitable packing 36 bearing against the outer surface thereof; said packing being carried by a sleeve 37 extending through the opening in the cover and welded to the cover. Sleeve 37 supports in its lower end a removable retainer ring 41 for the lower end of packing 36, and the upper part of sleeve 37 is surrounded and reenforced by a collar 42, which is welded at its lower end to the cover 21. The upper end of collar 42 carries a packing gland 44, the pressure of which against the packing 36 is adjustable by means of a clamping nut 45, which latter is secured by a lock nut 46. A thrust washer 50 of wood or other suitable material is inserted between the upper end of the gland 44 and clamping nut assembly 45 and the bottom of an apron 51 secured on the lower end of stationary connection 25. From the above it will be understood that an air-tight seal is maintained between the outer bearing surface of the stationary sleeve 35 on the one hand, and the bearing surfaces provided by the rotatable sleeve 41, packing 36, and gland 44 on the other hand.

The supply of milk into the reservoir through the open lower end of the tube 52 is controlled by a float 53 having a central sleeve 54, which is slideable vertically on the tube 24. This float is intended to maintain the surface of the liquid in the reservoir approximately at the level indicated at A. This level, of course, is dependent upon the degree of vacuum maintained in the reservoir, and the float is so designed that the surface of the liquid will not rise above the level B, even when a substantially perfect vacuum is established in the reservoir.

When the reservoir is filled to the proper level and the float is in its uppermost position, as shown in Fig. 2, a sealing element 55 carried by the float, bears against and closes the lower end of the milk supply tube 24. This sealing element 55 may be constructed of rubber or other suitable, relatively soft, resilient material, and is held in place in the lower end of the sleeve 54 by suitable means such as a plug 56, retained by means of a hairpin-like clip 57 which engages slots 60 in the lower end of tube 54, and slots in the plug as indicated in Figs. 2 and 9. Clip 57 also serves to hold in place on the lower end of sleeve 54, an inverted conical perforated screen 62, which has a reenforcing bearing washer 63 secured around and on the lower side of a centrally located opening in the strainer element. Normally, the strainer element is held in engagement with a washer 64 secured on the lower end of sleeve 54, but upon removal of clip 57, the strainer element may be removed downwardly from sleeve 54.

When the liquid in the reservoir is below the desired level, float 53 assumes a lowered position so as to permit milk to flow downwardly out of the bottom of tube 24 and thence laterally out through a plurality of slots 58 (see Fig. 8) in sleeve 54, and into the main body of milk in the reservoir through the perforations in strainer element 62.

If the float 53 were permitted to rotate with

the reservoir 21 and the body of milk therein, there would be an undesirable amount of wear on the closure element 85, due to rubbing against the lower end of the stationary tube 24. In order to prevent this, the sleeve 54 is provided with an upwardly projecting extension 65, which is arranged to engage a downwardly projecting extension 66 on the stationary sleeve 35, so as to stop rotation of the float.

The reservoir previously described is provided with a plurality of filler valves constructed in accordance with the present invention. Although only one of these valves is shown in detail on Figs. 2 to 6 of the drawings, it will be understood that the desired number of such valves are disposed around the bottom of the tank 20 at the proper arcuate distances apart, as indicated on Fig. 1, which will be referred to more in detail hereinafter.

Each of the valve assemblies is supported and guided by means of an outer stationary tube 78 having a flanged ferrule 71 welded or otherwise secured on the lower end thereof. When the valve assembly is inserted into an opening provided therefor in the bottom of the tank 20, the flange of ferrule 71 is securely held in place by means of a clamping nut 72, which engages a screw-threaded nipple 73 secured in the opening in the bottom of the tank by welding or otherwise, a suitable gasket being inserted between the bottom of the nipple 73 and the ferrule flange. This constitutes a conventional form of sanitary joint, and removal of nut 72 permits ready withdrawal of the whole valve assembly from the reservoir, so as to permit disassembly and cleaning of the valve parts.

Within tube 78 there is disposed a vertically slidable tube 76, on the lower end of which is welded a nozzle 77 formed with a circumferential flange 78 for a purpose hereinafter described. A sealing ring 80 is mounted on the nozzle 77 below flange 78 for engagement with the mouth of a bottle or other container to be filled. This sealing ring is made of rubber or other suitable material of sufficient softness and resilience, and the bottom thereof is conically shaped and provided with an annular groove 81, so that when the mouth of the bottle or other container is pressed against ring 80, an air-tight seal is insured, provided the rim of the bottle or container does not have cracks or other defects such as would render undesirable the use of the bottle or container.

In order to prevent stagnation of milk in the crevices in the joint between the valve assembly and the tank 20, which stagnation might cause contamination of the body of milk in the reservoir, a plurality of small vertically extending passages 82 are provided in the exterior surface of ferrule 71. The lower ends of these passages communicate with ports 83, extending radially through the ferrule and communicating with the slight clearance between the inner surface of the ferrule and the outer surface of the tube 78. This clearance communicates with the interior of tube 78 by means of openings 85 in the tube. Thus, any milk which might tend to collect in the crevices of the joint will flow downwardly through passages 82, ports 83, said clearance, and openings 85, into the filling passage within tube 78, and thereby will maintain all parts of the joint free from contamination. Said clearance is too slight to properly illustrate in the drawings.

Around the slidable tube 76 and below the ferrule 71 is a packing ring 86 of rubber or other suitable material, which is clamped in place by a

packing nut 87 in screw-threaded engagement with the lower end of the ferrule 71, so as to seal the joint between the stationary ferrule and the slidable tube 76. Packing nut 87 is formed at its upper end with an annular flange 88, which provides a bearing surface for the upper end of a compression spring 89, the lower end of which bears on the flange 78 and applies downward pressure on the tube 76 for a purpose to be described more in detail hereinafter.

Concentrically disposed within the tube 78 is a vertically movable tube 92, which, with the tube 78 forms an annular passage 93 for the flow of milk to the filling nozzle 77. The milk enters this passage from the interior of tank 20 through openings 94 in tube 78 and openings 95 in tube 78. Any suitable number and arrangement of these openings may be provided. However, in the illustrated embodiment, three openings 94 are provided in tube 78 at approximately 120° center to center spacing, while four openings 95 are provided in tube 78 at 90° center to center spacing. With this arrangement, and due to the somewhat larger circumferential width of openings 94, it is insured that some part of the openings 95 always will be in registry with some part of the openings 94, irrespective of differences in angular positioning of tube 78 relative to tube 76 which might result from variations in assembly.

The lower end of the tube 92 has a conical flared valve portion 96 arranged to engage the valve seat 97 on the lower end of nozzle 77 so as to close off the lower end of passage 93. The upper end of the tube 92 has an enlarged head or weight 100 disposed above and arranged to engage four inwardly projecting and generally triangular lugs 101 secured in the upper end of the tube 78. In order to provide for withdrawal of the tube 92 from the tube 78, when the valve parts are disassembled for cleaning purposes, the upper portion of tube 78 is provided with four slots 102 disposed in quadrature relationship (see Figs. 6, 11 and 15). This permits spreading apart of lugs 101, when the tube 78 is removed from the tube 92, to an extent sufficient to enable head 100 on tube 92 to be withdrawn past the lugs 101.

An elongated rod or plunger 105 is disposed concentrically within the tube 92, and is guided near its upper end for sliding movement relative to the tube 92 by means of triangular lugs 106 engaging the interior of enlarged portion 100 of the tube 92. At its lower end, rod 105 has an enlarged head 107 adapted to guide the lower end of the rod in tube 92, and which head is of such diameter as to provide a slight clearance 108 between it and tube 92. This clearance is shown as exaggerated in Fig. 3a, as the actual amount would not clearly appear in a scale drawing. A plurality of curved cutaway portions 110 are provided in head 107 for the free flow of air into the lower end of tube 92 when the air valve is fully open, as hereinafter described. The extreme lower end of this head is formed with a conical enlargement 111, constituting a valve engageable with the valve seat 112 at the inner lower end of the tube 92 to completely shut off the flow of air into the air passage 113 formed between rod 105 and the tube 92.

Adjacent to the upper end of the rod are two enlargements or stops 114 and 115, disposed in vertically spaced relationship and arranged for engagement with the upper and lower faces, respectively, of an abutment member 116, which is in the form of a bifurcated spring clip. This spring clip extends into and is supported by a

pair of slots 117 disposed in opposite sides of the upper end portion of stationary tube 76. These abutments are so spaced as to form lost motion connections between the rod and tube 76 and limit the range of movement of the rod to an amount less than the range of movement of the tubes 76 and 92. On the extreme upper end of rod 105 there is slidably mounted a cylindrical block 120, the weight of which is so calibrated that it will operate as hereinafter described. The block is prevented from dropping off of the rod during removal of the valve assembly from the reservoir, by means of a projection 121 on the upper end of an upwardly extending arm 122 of clip 116.

When the apparatus described is used for the filling of bottles, a proper vacuum, as for example from about 20" to about 28" of mercury will be maintained in the reservoir 20 by suitable means attached to the connection 31. Suitable means are also provided for supplying milk to the reservoir through the tube 24, so that under the control of float 53 and the valve 55, the level of the milk is maintained in the reservoir approximately at the level indicated at A on Fig. 2, and below the upper end of the tube 92. Normally, when no bottle is in engagement with the filling valve, the parts will be in the position shown in Fig. 3 and the stop 114 on the rod 105 is held in engagement with the upper surface of abutment 116, and the rod is maintained under tension by the action of the compression spring 89 on the flange 78. The spring 89 is of sufficient strength to hold the rod 105 and the tubes 76 and 92 down against the action of the vacuum maintained in the interior of the reservoir and the valve casing 70. Thus the flared head 111 on the rod 105 is maintained in tight engagement with the valve seat 112 of the tube 92, and the conical flange or valve 96 on the tube 92 is maintained in tight engagement with valve seat 97 of nozzle 77, so as to thereby seal the milk passage 93 and the air passage 113. Hence, when the valve is not being employed for the filling of a bottle, there is no leakage or dripping of milk from the passage 93, and no leakage of air into passage 113, and thence into the milk reservoir.

When it is desired to fill a bottle with the apparatus described, a bottle C is brought into position beneath the filler valve and is raised to cause engagement of the mouth of the bottle with the filler valve. Thus a tight seal is effected between the neck of the bottle and the sealing ring 80, if the rim of the bottle neck is reasonably regular and has no cracks or serious breaks. Further upward movement of the bottle raises the slideable tube 76 against the downward pressure of the spring 89. The tube 92 and the rod 105 also move upwardly due to the differential in pressure between the interior of the bottle, which is at atmospheric pressure, and the evacuated interior of the reservoir or tank 20. After a limited and predetermined upward movement of the tubes 76 and 92 and the rod 105, the enlargement 116 on the rod engages the abutment 116, as indicated at the upper part of Fig. 4. This prevents further upward movement of the rod, while the two tubes continue to move upwardly a slight additional distance to effect disengagement of valve seat 112 from the valve head 111 on the lower end of the rod 105. This permits air to be drawn through the restricted valve clearance 108 between the tube 92 and the head 107 into air passage 113, tending to produce a vacuum in the bottle. If there are no cracks or other defects

permitting leakage of air into the bottle, the bottle soon is evacuated to a predetermined partial vacuum, as for example about 13" of mercury. The weight of the rod and the weight of the block 120 on the upper end of the rod are so calibrated in accordance with the vacuum to be maintained in the reservoir, that when, and only when, the predetermined partial vacuum is produced in the bottle, the rod drops to its fully open position shown in Fig. 5, with the enlargement 114 resting on the abutment 116. This opens wide the valve opening at the lower end of air passage 113, allowing free flow of air through cut-away portions 110 of valve head 107, so that the remainder of the air in the bottle is quickly withdrawn and a vacuum approximately equal to that in the reservoir is produced in the bottle. When substantial equalization between the pressures in the bottle and in the reservoir is produced, the tube 92 drops to the position shown in Fig. 6, so as to thereby open wide the lower end of milk passage 93 and permit rapid filling of the bottle. During this filling operation, head 100 of tube 92 rests on lugs 101 so that the lower end of air passage 113 is not completely closed and any residual air in the bottle is withdrawn through the clearance around the head 107.

The final milk level in the bottle is determined by the shape of the sealing ring 80, and the distance this ring projects into the bottle mouth, and the operation just described results in complete filling of the bottle to the proper level without any aeration of the milk. The timing of the movement of the bottles is so controlled, as will be understood by one skilled in the art, that when sufficient time, which is in the order of only a few seconds, has elapsed for completion of the filling operation, the bottle is moved downwardly and retracted from engagement with the valve. This permits the tube 76 to move downwardly under the influence of the spring 89, so that the milk passage 93 and the air passage 113 again are tightly closed at valve seats 97 and 112, as previously described, thus preventing dripping of milk from the valve and leakage of air into the reservoir.

The foregoing description of operation is based upon the assumption of a bottle having no cracks or other defects which would permit leakage of air into the bottle. If such a defective bottle is encountered, no liquid is delivered to it because when the mouth of the bottle engages and elevates the tubes 76 and 92, the rod 105 also will be raised until a restricted opening is produced at the lower end of air passage 113, as previously described, and the parts assume the positions indicated in Fig. 4. A throttled amount of air then will be drawn from the bottle around the head 107, but due to leakage of air from the atmosphere into the bottle, it will be impossible to produce in the bottle the predetermined degree of partial vacuum necessary to cause rod 105 to drop to its fully open position shown in Fig. 5. Thus the small amount of air which will be drawn up through passage 113 into the evacuated space over the milk in the reservoir will be insufficient to produce harmful effects on the milk, and loss of vacuum and overtaxing of the evacuating equipment will be prevented. Also, as will be recalled from the previous description, tube 92 will not drop to open or filling position, since equalization of pressure between the reservoir and the interior of the bottle cannot be accomplished when a broken bottle is encountered. Hence, since the milk passage 93 will remain completely closed, there will

be no danger of air bubbling up through and aerating the milk in passage 93. As a result of this important feature of the invention, a defective bottle will remain unfilled and will be rejected without any necessity for observation or action on the part of an operator, and no harmful effects, from the standpoint of either the evacuating equipment or the milk in the filling apparatus, will be produced by reason of the leakage of air into the defective bottle. When the predetermined time for filling has elapsed, the bottle will be lowered out of engagement with the valve and the valve passages will be tightly closed.

The apparatus above described may be incorporated in various different types of filling machines and any suitable mechanism may be provided for effecting the relative vertical movement of the bottle and the reservoir 20. Merely as an example, there is shown in Fig. 1 a machine, the details of the lower portion of which constitute no element of novelty or portion of my invention. In the mechanism there shown there is provided a base 130 with a platform 131 and a vertically disposed rod 132 on which is mounted the rotatable standard 133 which supports the reservoir 20. The standard has any suitable means for rotating it such as a worm wheel 134 engaging a worm 135 and also carries a spider 136 in which is mounted an annular row of vertically movable plungers 137. On the upper ends of these plungers are mounted bottle supports 138 vertically slidable in the platform 131 and each provided with a bracket or other suitable positioning means 139 for holding the bottles in place and in alignment with the filling nozzles. The plungers 137 have rollers 140 which travel on the upper surface of a non-rotatable cam 141. The cam is of such shape that when the roller is at the lower portion of the cam surface, the bottle on said support will be spaced below and out of engagement with the corresponding nozzle on the reservoir. As the standard 133 rotates, the roller will travel up the cam to lift the bottle into engagement with the nozzle as shown at the left of Fig. 1 and in Fig. 3, and then further lift it to move the nozzle into the position shown in Fig. 4. The cam is of such shape that when the bottle has moved laterally for a sufficient time interval to permit it to be evacuated and then filled, it will be lowered out of engagement with the nozzle and the bottle removed and replaced by an empty one.

In Figs. 16 and 17 there is shown a modified form of nozzle embodying my invention and which may be used with the reservoir shown in Figs. 1 and 2 by proper modification of the reservoir so that the nozzles connect to the peripheral wall of the reservoir instead of to the bottom thereof. This modified nozzle includes in general a stationary T-shaped housing 150 which may be welded or otherwise secured to the side wall of the reservoir 20. Within the vertical section of this housing are an outer slidable tube 76a, an inner slidable tube 92a, and a rod 105a. The tubes 76a and 92a and the rod 105a correspond fundamentally to the tubes 76 and 92 and the rod 105, respectively, of the previously described embodiment. They have the same type of valve mechanism and normally are pressed downwardly to their lowermost positions by means of compression spring 89a. When the tubes and rod are in their non-filling positions illustrated in Fig. 16, the milk passage 93a and the air passage 113a are maintained tightly closed at their lower ends. Outer tube 76a has a sealing ring 80a on its lower end for engagement with the neck of a bottle C 75

or other container. Tube 76a is slidable in a bearing sleeve 70a mounted in the lower end of housing 150, and the sliding joint between the tube and the housing is sealed by a packing 86a of rubber or other suitable material, which is held in place and compressed by packing nut 87a screw-threaded on the lower end of housing 150. The inner tube 92a is guided at its upper end by a removable, U-shaped washer 101a supported in the upper end of tube 76a, and tube 92a is prevented from withdrawal from tube 76a by engagement of a flange or enlargement 108a with washer 101a. The outer tube 76a is provided with an opening 95a to permit flow of milk into passage 93a. The valve housing 150 is intended to be mounted in such manner that the level of milk will not rise above the center line of the horizontal branch of the T-shaped housing 150 under any conditions of vacuum in the reservoir, and the evacuated space above the milk in the reservoir is in communication with air passage 113a through the top of tube 92a.

The upper end of housing 150 is closed by an abutment disc 116a, held in place by a flange 151, which is clamped by a nut 152. Flange 151 is welded or otherwise secured on the lower end of a housing 153 which serves to enclose a spring 154 for pressing the rod 105a downwardly. The rod 105a has stops or abutments 114a and 115a on opposite sides of the abutment disc 116a so as to provide lost motion connections and to limit the range of movement of the rod 105a. Under normal conditions, when no bottle is being filled, the stop 114a adjacent the upper end of rod 105a rests on the upper end of disc 116a and the rod 105a is maintained under tension by spring 89a.

When a bottle is placed on an elevatable platform, such as the platform referred to in the previous description, and the platform is raised, the neck of the bottle engages sealing ring 80a and raises the outer tube 76a. Tube 92a and rod 105a also move upwardly due to the vacuum in the reservoir, so that the lower ends of milk passage 93a and air passage 113a are maintained tightly closed. When stop 115a on the rod 105a hits abutment 116a, the rod stops its upward movement while tubes 76a and 92a continue upwardly a slight distance. This has the effect of producing a restricted passage at the lower end of air passage 113a. If the bottle should happen to be cracked so that air may enter into it, the restricted opening between the lower ends of rod 105a and tube 92a prevents free rush of air into the valve body and reservoir, and thus prevents contamination of the milk in the reservoir and overtaxing of the evacuating equipment, in the manner described in connection with the previous embodiment.

On the other hand, if the bottle is sound, a vacuum is drawn therein, and when this vacuum reaches a predetermined degree, as for example 13 inches of mercury, rod 105a drops due to its own weight and the predetermined calibration of spring 154. With the rod in its lowermost position, completion of the evacuation of the bottle quickly takes place as in Fig. 5. As soon as the pressures in the bottle, the valve body and the reservoir are substantially equalized, tube 92a drops to its position shown in Fig. 6, thereby opening the outer milk passage 93a so as to effect rapid filling of the bottle.

A further modification, which may be applied to the structure of Fig. 16, is illustrated in Fig. 18. In this latter embodiment, the upper end of housing 153b is closed only by a flexible rubber

sack or diaphragm 155, so that rod 15a is pressed downwardly by its own weight plus the action of atmospheric pressure on the upper end of the rod. The area of the upper end 14b of the rod is made such that a predetermined downward pressure is exerted on the rod, which pressure, in combination with the weight of the rod, is such as to effect dropping of the rod to the position indicated in Fig. 5, only when the predetermined partial vacuum such as, for example, 13 inches of mercury, is produced in the bottle.

Various other modifications may be readily devised within the scope of my invention.

Having thus described my invention, what I claim as new and desire to secure by Letters Patent is:

1. In an apparatus for filling a container with liquid, a filling nozzle having a vacuum passage and a liquid passage, a pair of valves for closing said passages, means operated by a movement of said nozzle with the container for partially opening the valve of said vacuum passage, and means operative responsively to the development of a predetermined degree of vacuum in said container for further opening said last mentioned valve and for opening the other of said valves to permit flow of liquid.

2. In an apparatus for filling a container with a liquid, the combination of a filling nozzle having passages for communication with the interior of the container, valve mechanism for controlling said passages, means for applying a vacuum to one of said passages, means for supplying liquid to the other of said passages, positively operating means for operating said valve mechanism to partially open the vacuum passage upon a predetermined relative movement of said nozzle and said container, and means automatically operative upon a predetermined drop in pressure in said container for operating said valve mechanism to open said vacuum passage to a further extent and to thereafter open the liquid passage as the vacuum in said container progressively increases.

3. In an apparatus for filling a container with a liquid, the combination of a filling nozzle having passages for communication with the interior of the container, means for applying a vacuum to one of said passages, means for supplying liquid to the other of said passages, positively operating means for partially opening the vacuum passage upon a predetermined movement of said passages with said container, and means automatically operative upon decrease in pressure in the container for opening said vacuum passage to a further extent and thereafter opening the liquid passage.

4. In an apparatus for filling a container with a liquid, the combination of a filling nozzle having a vacuum passage and a liquid supply passage for communication with the interior of the container, valve mechanism for controlling flow of fluid in said passages, means mechanically operable for effecting operation of said valve mechanism to partially open the vacuum passage, means operative responsively to a predetermined drop in pressure in the container for further opening said vacuum passage, means operative responsively to a predetermined and greater drop in pressure in the container for further operating said valve mechanism to open the liquid passage and partially close the vacuum passage, and means operative automatically upon removal of

the container from said nozzle for closing both said passages.

5. In an apparatus for filling a container with a liquid, the combination of a filling nozzle having a liquid passage and a vacuum passage for communication with the interior of the container, a valve for said vacuum passage, a separate valve for said liquid passage, means operative by bodily movement of said nozzle with said container for partially opening said first mentioned valve, means operative automatically upon a predetermined drop in pressure in the container for further opening said first mentioned valve, means automatically operative upon a further drop in pressure in said container for opening the second mentioned valve, and means operative by removal of the container from said nozzle for closing both said valves.

6. In an apparatus for filling a container with a liquid, the combination of a filling nozzle having a pair of passages for communication with the interior of the container, valve mechanism for controlling said passages, means for applying a vacuum to one of said passages, means for supplying liquid to the other of said passages, means operative by relative bodily movement of said nozzle and said container for operating said valve mechanism to partially open the vacuum passage, a weight operating said valve mechanism to further open said vacuum passage when the pressure in the container drops below a predetermined limit, a separate weight for operating said valve mechanism to open the liquid passage when the pressure in said container drops below a lower predetermined limit, and means operative automatically upon removal of said container from said nozzle for operating said valve mechanism to close both said passages.

7. In an apparatus for filling a container with a liquid, the combination of a filling nozzle having sealing means for engaging the inlet of the container and having passages for communication with the interior of the container, valve mechanism for controlling said passages, means for applying a vacuum to one of said passages, means for supplying liquid to the other of said passages, means operative by bodily movement of said nozzle with said container for operating said valve mechanism to partially open the vacuum passage, means for automatically opening said vacuum passage to a further extent when air has been withdrawn from the container to a predetermined extent, means for opening the liquid passage when the pressure in the container has been lowered to a further extent, and means operative upon disengagement of said container from said nozzle for operating said valve mechanism to close both said passages.

8. A nozzle for filling containers with liquid including a pair of concentric vertically movable tubes, a vertically movable rod within the inner tube and having a range of vertical movement less than that of said tubes, valve mechanism for closing both of said tubes, and means for operating said valve mechanism to open the lower end of the inner tube when said inner tube is moved upwardly beyond the limit of upward movement of said rod, and to open the lower end of the outer tube when a sufficient vacuum has been created in the container to permit the inner tube to drop by gravity.

9. In an apparatus for filling a container with liquid, a filling nozzle having a pair of concentric tubes, means for applying a vacuum to the upper end of the inner tube, means for supplying liquid

to the outer tube, a pair of valves at the lower end of said nozzle for closing said tubes, positively operating means for partially opening the valve of said vacuum tube by an upward movement of said nozzle and the container, means for automatically further opening said last mentioned valve and thereafter opening the valve of the liquid tube when the vacuum obtained in said container has reached a predetermined limit, and means operable upon the removal of the container from said nozzle for closing both of said valves.

10. An apparatus for filling containers with liquid, including a reservoir for the liquid, means for maintaining said reservoir under partial vacuum, means for maintaining a substantially constant liquid level in said reservoir, a pair of concentric vertically movable tubes, the inner tube communicating with said reservoir above said liquid level and the outer tube communicating with the reservoir below said liquid level, a vertically movable rod within the inner tube, means for limiting the range of movement of said rod to an amount less than the range of movement of said tubes, valve mechanism for closing the lower ends of both of said tubes, said valve mechanism operating to open the lower end of the inner tube when said inner tube is moved upwardly beyond the limit of upward movement of said rod, and operating to open the lower end of the outer tube when a sufficient vacuum has been created in the container to permit the inner tube to drop by gravity.

11. In an apparatus for filling a container with liquid, a filling nozzle having a pair of tubes, means for applying a vacuum to the upper end of one of said tubes, means for supplying liquid to the other of said tubes, a pair of valves at the lower end of said nozzle for closing said tubes, means operated by an upward movement of said nozzle and the container for partially opening the valve of said vacuum tube, said last mentioned valve being automatically opened to a further extent when a predetermined vacuum is obtained in said container, and the other of said valves being automatically opened to permit inflow of liquid when a higher predetermined vacuum is obtained in said container, and means for closing both of said valves upon a downward movement of said nozzle and said container.

12. In an apparatus for filling a container with liquid, a filling nozzle having a pair of concentric tubes, means for applying a vacuum to the upper end of the inner one of said tubes, means for supplying liquid to the outer of said tubes, a pair of concentric valves at the lower end of said nozzle for closing said tubes, positive means for partially opening the valve of said vacuum tube upon an upward movement of said tubes, said valve being automatically opened to a further extent when a predetermined vacuum is obtained in said container, the other of said valves being automatically opened to permit inflow of liquid and said first mentioned valve being partially closed when a higher predetermined vacuum is obtained in said container, and means for closing both of said valves by a downward movement of said nozzle and said container.

13. An apparatus for filling containers with liquid from a reservoir under vacuum, including a pair of concentric vertically movable tubes, a vertically movable rod within the inner tube, the range of movement of said tubes being greater than that of said rod, a valve on the lower end of said rod for closing the lower end of the inner

tube, a valve on the lower end of the inner tube for closing the lower end of the outer tube, said inner tube and said rod being automatically raised due to differences in pressure in the reservoir and the container during mechanical raising of the outer tube, said first mentioned valve being mechanically opened upon the vertical movement of the two tubes beyond the range of movement of the rod, and said inner tube automatically dropping by gravity to open the second mentioned valve when the pressure in the container has dropped to a predetermined limit.

14. An apparatus for filling containers with liquid including a pair of concentric vertically movable tubes, the inner tube communicating with a source of vacuum and the outer tube communicating with a source of liquid, a vertically movable rod within the inner tube, the range of movement of said tubes being greater than that of said rod, a valve on the lower end of said rod for closing the lower end of the inner tube, a valve on the lower end of the inner tube for closing the lower end of the outer tube, and a weight having lost motion connection with said rod, said first mentioned valve being opened upon the vertical movement of said tubes beyond the limit of movement of said rod, said weight serving to move said rod to its lower limiting position upon a predetermined drop in the pressure in the container, and said inner tube being free to drop by gravity and open said second mentioned valve when the pressure in the container, due to the escape of air from the latter through said inner tube, reaches a lower predetermined limit.

15. A nozzle for filling containers with liquid including a pair of concentric vertically movable tubes, the inner tube for application of a vacuum to the container and the outer tube for the supply of liquid to the container, a vertically movable rod within the inner tube, the range of vertical movement of said tubes being greater than that of said rod, a valve on the lower end of said rod for closing the lower end of the inner tube, a valve on the lower end of the inner tube for closing the lower end of the outer tube, the outer tube upon being raised, permitting raising of said inner tube and said rod, said first mentioned valve being mechanically opened upon the vertical movement of the two tubes beyond the range of movement of the rod, and said inner tube automatically dropping by gravity to open the second mentioned valve when the pressure in the container has dropped to a predetermined limit.

16. An apparatus for filling containers with liquid including a pair of vertically movable tubes, one tube communicating with a source of vacuum and the other tube communicating with a source of liquid, a vertically movable rod, the range of movement of said tubes being greater than that of said rod, a valve on the lower end of said rod for closing the lower end of the first mentioned tube and a valve on the lower end of said first mentioned tube for closing the lower end of the second mentioned tube, said first mentioned valve being opened upon the vertical movement of said tubes beyond the limit of movement of said rod, and said first mentioned tube being free to drop by gravity and open said second mentioned valve when the vacuum in the container, due to the escape of air from the latter through said first mentioned tube, reaches a predetermined limit.

17. An apparatus for filling containers with liquid including a pair of concentric vertically movable tubes, the inner tube communicating

with a source of vacuum and the outer tube communicating with a source of liquid, a vertically movable rod within the inner tube, the range of movement of said tubes being greater than that of said rod, a valve on the lower end of said rod for closing the lower end of the inner tube, and a valve on the lower end of the inner tube for closing the lower end of the outer tube, said first mentioned valve being positively opened upon the vertical movement of said tubes beyond the limit of movement of said rod and said inner tube being free to drop by gravity and open said second mentioned valve when the vacuum in the container, due to the escape of air from the latter through said inner tube, reaches a predetermined limit.

18. A nozzle for container filling apparatus including a pair of concentric vertically movable tubes, the inner tube affording an evacuating passage and the outer tube affording a passage for the liquid to be delivered to the container, a valve at the lower end of the inner tube and having seating engagement with the lower end of the outer tube, a vertically movable rod within the inner tube and having a valve at its lower end for seating engagement with the lower end of the inner tube, lost motion connections for limiting the movement of said rod to a range less than that of said tubes, means on said nozzle for closure engagement with the inlet of a container to be filled whereby upon upward movement of said container, said tubes and rods are simultaneously lifted, with both of said valves in closed position, until said lost motion connections limit the upward movement of said rod and said tubes are lifted to a further extent to thereby partially open said second mentioned valve, said rod being free to drop and further open said second mentioned valve when the vacuum in the container reaches a predetermined limit and said inner tube being free to drop and thereby open the first mentioned valve when the vacuum in the container reaches a lower predetermined limit.

19. A nozzle for container filling apparatus including a pair of concentric vertically movable tubes, the inner tube affording an evacuating passage and the outer tube affording a passage for a liquid supply, a valve at the lower end of the inner tube and having seating engagement with the lower end of the outer tube, a vertically movable rod within the inner tube and having a valve at its lower end for seating engagement with the lower end of the inner tube, means for limiting the range of movement of said rod to a lesser range than that of said tubes, means on said nozzle for engagement with the mouth of a container and whereby upon upward movement of said container, said tubes and rods are simultaneously lifted to the same extent with said valves in closed position, until the limit of upward movement of said rod is reached and upon further upward movement of said tubes, said second mentioned valve is partially opened and said rod dropping by gravity to its lower limiting position when the vacuum in the container reaches a predetermined limit and the inner tube dropping by gravity and opening the first mentioned valve when the vacuum in the container reaches a lower predetermined limit.

20. An apparatus for filling containers with liquid, including a reservoir for the liquid and provided with connections for delivering liquid to said reservoir and for maintaining said reservoir

under partial vacuum, means for controlling the delivery of liquid to said reservoir to maintain a substantially constant level therein, a pair of concentric vertically movable tubes, the inner tube communicating with said reservoir above said liquid level and the outer tube communicating with the reservoir below said liquid level, a vertically movable rod within the inner tube and having lost motion connections with a wall of said reservoir, and valve mechanism for closing the lower ends of both of said tubes, said valve mechanism operating to open the lower end of the inner tube when said inner tube is moved upwardly beyond the limit of upward movement of said rod, and operating to open the lower end of the outer tube when a sufficient vacuum has been created in the container to permit the inner tube to drop by gravity.

21. A nozzle for use in an apparatus for evacuating a container and delivering liquid thereto, said nozzle being removably engageable with said container and having a passage for the withdrawal of air from such container, a passage for delivery of liquid to said container, and means operative dependently upon the pressure in such container, when the latter is in engagement with said nozzle, for automatically opening said liquid delivery passage when, and only when, a predetermined vacuum is produced in the container.

22. A nozzle for use in an apparatus for evacuating a container and delivering liquid thereto, said nozzle being removably engageable with said container and having a normally closed evacuating passage and a normally closed liquid delivery passage, means operable to effect opening of said evacuating passage so as to permit withdrawal of air from a container engaged with said nozzle, and means operative dependently upon the pressure in such container for automatically opening said liquid delivery passage when, and only when, a predetermined vacuum is produced in the container.

23. A nozzle for use in an apparatus for evacuating a container and delivering liquid thereto, said nozzle being removably engageable with said container and having a normally closed evacuating passage and a normally closed liquid delivery passage, means operable to effect partial opening of said evacuating passage upon pressure engagement with said nozzle, and means operated dependently upon the resulting drop in pressure in such container for effecting further opening of said evacuating passage, and thereafter automatically opening said liquid delivery passage upon production of a predetermined vacuum in the container.

24. A nozzle for use in an apparatus for evacuating a container and delivering liquid thereto, said nozzle being removably engageable with a container to be filled and having an evacuating passage and a liquid delivery passage, valves normally closing said passages, means operable to effect partial opening of the evacuating passage valve so as to permit withdrawal of air from a container engaged with said nozzle, and means operative automatically in response to production of predetermined degrees of vacuum in such container for effecting further opening of said evacuating passage valve and thereafter effecting opening of the other of said valves to permit flow of liquid to the container through said liquid delivery passage.

BRUCE DE HAVEN MILLER.
